UNITED STATES PATENT OFFICE.

JAMES M. WILSON, OF NEWARK, NEW JERSEY, ASSIGNOR TO SPLITDORF ELECTRICAL COMPANY, OF NEWARK, NEW JERSEY.

END PLATE FOR COMBINED IGNITING AND LIGHTING GENERATORS.

1,260,843.

Specification of Letters Patent. Patented Mar. 26, 1918.

Application filed June 30, 1915. Serial No. 37,202.

To all whom it may concern:

Be it known that I, JAMES M. WILSON, a citizen of the United States, residing at Newark, in the county of Essex and State 5 of New Jersey, have invented certain new and useful Improvements in End Plates for Combined Igniting and Lighting Generators, of which the following is a specification.

My invention relates to improvements in 10 generators used for both ignition work and lighting, in which the ignition current is generated within the machine and delivered direct to the spark plugs or ignition devices of an internal combustion engine and the 15 current for lighting the lamps and charging the battery of the vehicle to which the generator is attached is generated in the same machines, but from a separate armature.

20 My present invention is directed to ways and means for mounting the igniting and lighting armatures within the same magnetic field frame, so that in case of necessity, the armatures may be readily removed for 25 the purpose of inspection and repair.

In order to accomplish this purpose, I have provided a combination of end plates which are adapted to be quickly attached or detached from the field frame. The end 30 plates serve to carry the bearing supports for the two armatures and as housing for the electrical connectors and mechanical devices used in connection with the operation of the entire structure.

35 In my application, Serial Number 832539, filed April 17, 1914, patented March 20, 1917, Patent No. 1,219,518, I have shown a sectional view of my igniting and lighting generator having the end plates which constitute the subject of this application.

40 Referring now particularly to the drawings, Figure 1 is a longitudinal sectional elevation of my combined igniting and lighting generator diagrammatically illustrated 45 in Fig. 7, showing, however, only the end plates in section.

Fig. 2 is a left hand end view of Fig. 1 with the cover plates removed from the plates which house the circuit interrupters for both 50 armatures.

Fig. 3 is an end view of the righthand end plate of Fig. 1.

Fig. 4 is a side elevation of Fig. 3 but with the end plate cap or commutator hous-

ing for the lighting armature slightly withdrawn from the end plate. 55

Fig. 5 is an end view of the two larger end plates of the left side of Fig. 1.

Fig. 6 is a side elevation of Fig. 5 but with the outer end plate slightly withdrawn from 60 the inner end plate.

Fig. 7 is a diagrammatical illustration of the circuit arrangement used in one form of my invention and is the same as Fig. 7 of my application, Serial No. 832539 above 65 referred to.

Fig. 8 is an end view of an auxiliary plate mounted on the outer plate of Fig. 6 and carrying the contact switching members shown in Fig. 7. 70

Fig. 9 is a section on the line A—B of Fig. 8.

Fig. 10 is a modified form of an auxiliary plate carrying switch members.

Referring now particularly to the drawings in which like numerals refer to corresponding parts in the various views, 1 is a base of non-magnetic material to which is attached in any suitable manner, pole pieces 2 and 3. These pole pieces have extensions 52 and 4 to which are attached by any suitable means, such as screw, pole pieces 5 and 6. Bridging the extensions 52 and 4 is a yoke 7 carrying a coil 8. Mounted on the pole pieces 5 and 6 are field coils 9 and 10. 85 Between the pole pieces 2 and 3 and mounted on suitable bearings 11 and 12 (shown in Fig. 1) is a high tension armature 16 of a type particularly adapted for firing a two cylinder engine in which the cylinders are 90 placed at an angle. The current in the primary winding of the high tension armature 16 passes through the circuit breaker 22 and is interrupted at the proper intervals by means of the cams 13 and 14 located 95 within the cam holder which is mounted on one of the end plates 34. The high tension current is taken off the spool 15 by brushes in the usual manner and is conducted to the spark plugs in the usual manner. 100

Mounted above the ignition armature 16 on suitable bearings 18 and 19 is a low tension armature 17 which is driven by means of gear-wheel 20 attached to one end of the armature shaft through the medium of gear-wheel 21 that is fastened to the ignition armature 16. On the end of the generator shaft is mounted a sleeve 23 which is free 105

to slide back and forth on the end of the shaft 33. Attached to the gear-wheel 20 is a plate 24 having a hub 90 which is rigidly fitted to the inner race of the radial bearing 19. The hub 90 is keyed to shaft 33 in such a way that the armature 17 may be readily removed without disturbing the gear or bearing. This is an important feature for convenience of repairs since the D. C. armature may be removed without disturbing the high-tension or ignition armature. The plate 24 carries governor weights 25 pivoted in any well known manner. Mounted in the end of the sleeve 23 is a ball 26 which runs 15 against the friction bearing plate 27. This friction bearing plate is attached to a movable spring 28, which carries a contact 29. Mounted in any suitable manner within the auxiliary plate 30 is a stationary member 31 carrying an adjustable contact 32. Members 23—24—25 and 26 constitute a centrifugal governor which operates in accordance with the speed of rotation of the armature to close and open the contacts 29 and 32. The members 28 and 31 are both suitably insulated 25 from the auxiliary plate 30. Also mounted within the auxiliary plate 30 is a somewhat resilient contact member 47 which carries the contact 48. The position of this member 47 and its contact 48 is determined by means of an adjustable stop 36 which is carried by member 31. The adjustable member 36 however, has an insulating piece 35, such as fiber, interposed between it and the 30 member 47. The members, 28, 31 and 47 have holes 37, 38 and 39 through which contact studs, 40, 41 and 42 are adapted to pass and to make electrical contact therewith by means of suitable nuts screwed on 40 to the said studs. Proper electrical connections are made to the inner end of said studs 40, 41 and 42 and by means of them, these connections are brought to the governing switch contact elements 28, 47 and 31. The 45 said studs, 40, 41 and 42 are insulated from but fastened securely to the plate 43 by suitable bushings and insulators.

The end plate 43 carries an oil cup 44 for the purpose of oiling the bearing 19. The 50 end plate 43 has a shoulder 45 adapted to fit within corresponding grooves, not shown, on pole pieces 2 and 3 in the diagrammatic arrangement shown in Fig. 7. After the plate 43 is mounted on the field frame of the generator by means of four screws through holes 55 being centered thereon by the annular shoulder 45, plate 34 is placed in position on plate 43, being guided by the dowel pins 49 and the annular shoulder 50 which is 55 fitted to the inner surface of the plate 43. The dowel pins 49 project on both sides of plate 34 and their outer ends serve to guide the auxiliary plate 30 by means of the holes 51. Screws 75 are then passed through the 60 holes 54 into the plate 43, thereby holding the supplemental plate 34 and the auxiliary plate 30 in position on the plate 43. The supplemental plate 34 carries oil cups 56 for the purpose of oiling bearing 12. An annular steel bearing ring 57 mounted within the boss 58 of the plate 34 provides a bearing for the cam holder 59. Also mounted within the boss is a plate 60 of good wearing material, such as bronze, upon which the ground brush, mounted on the backside of 70 the circuit breaker 22, runs. 61 is a slot in the bottom portion of the boss within which the stop pin 62 of the cam holder 59 moves. A cover 63 is adapted to fit on the auxiliary plate 30 to protect the circuit controlling 75 springs, heretofore described, while a second cover 64 fits on the cam holder 59 to protect the circuit breaker mechanism 22.

Attached to the right hand end of the field pieces 2 and 3 by means of screws passing through the hole 65, is a main end bearing plate 66. Two additional screws are used to pass through the holes 84 and enter the polar extensions 52 and 4 to assist in holding the plate 66 securely in position on 80 the field frame. The upper portion of this plate is adapted to carry a commutator housing or cap 67, the same being held to the main plate 66 by means of screws passing through the holes 88. In Fig. 4 the cap or 85 housing 67 is shown withdrawn from the plate 66. The cap has an annular flange 68 which fits within the annular opening 69 of the plate 66. The cap 67 carries an oil cup 70 for the purpose of oiling the bearing 100 18, shown in Fig. 1. Mounted on but insulated from the cap 67 are brush holders 71. These brush holders carry brushes which run on the commutator of the armature 17. The lower portion of the plate 66 has the 105 boss 72, the opposite sides being machined flat to accommodate brush holders which are fastened to the boss by means of screws entering the holes 73. One portion of these brush holders enters the hole 74 and supports brushes that run on collector spool 15, which, in the case of a two cylinder machine carries a segment something less than 180 degrees. These brush holders and other details relating thereto, since they form no 110 part of this invention, are not shown. An oil cup 75 is carried on the upper portion of the boss 72 for the purpose of oiling the bearing 11. Mounted on but insulated from the plate 66 at the top thereof are three connecting studs, 76, 77 and 78. These studs are used for making the electrical connections with the interior of the machine as well as to the exterior circuits. The commutator housing or cap 67 has an opening 79 in the 115 top for a cover plate, not shown in Fig. 4 but adapted to be held thereto by means of screws entering the screw holes 80. This cover plate is used for the purpose of inspecting the commutator. A cap 81 is adapt- 120

ed to fit around a rim 82 for the purpose of covering the commutator housing and the circuit studs 76, 77 and 78. The cap is held in place by screws which enter the holes 83 in the end of the commutator housing 67.

Surrounding the field structure which carries the two armatures, exciting and regulating coils, etc., I place a cover 85 which fits in the groove 86 of plate 43 and around 10 the rim 87 of plate 66.

It will be seen that I have arranged the end bearing plates of my generator in such a manner that they may be readily applied to the field structure and that the plates for 15 each end of the generator forming as it were units, which carry the necessary bearings and electrical connecting studs. The use of the connecting studs, securely fastened to the end plates constitutes an important 20 feature of my invention as these fastening studs do away with a lot of flexible wiring which in the operation of the generator on a motorcycle where vibration is excessive is apt to become displaced and the insulation 25 worn, thereby causing trouble. By making the interior connections to the inner portion of the studs and extending these connections to the outer plates through insulating bushings, considerable time is saved 30 in the assembly of the generator and a much better job, both electrically and mechanically, is obtained.

It will also be seen that by the use of suitable covers for various parts that I have 35 made my generator as nearly water and dust proof as it is possible to construct it.

It will be apparent to anyone skilled in the art that numerous changes and alterations can be made in certain details but 40 these alterations and changes are believed to come within the scope of the appended claims.

Having thus described my invention, what I claim is:—

45 1. In combination a field frame with pole pieces attached thereto, two armatures for the generation of different kinds of current disposed adjacently between said pole pieces, main end plates attached to said field frame, 50 a supplemental and auxiliary plate both fastened by a common means to one of said main end plates, a housing fastened to the other of said main end plates, two bearings for one of said armatures, one of said bearings being carried directly by one of said main end plates and the other by said housing, two bearings for the other armature, one of said bearings being carried in said supplemental plate and the other bearing 55 carried in the main end plate which supports said housing.

60 2. In combination, a field frame with pole pieces attached thereto, two armatures disposed adjacently between said pole pieces, 65 end plates attached to said field frame for

supporting said armatures, a supplemental plate attached to one of said end plates, an auxiliary plate attached to said supplemental plate and carrying members included in the working circuit of one of said armatures 70 and a cover for said auxiliary plate, as described.

3. In combination, a field frame with pole pieces attached thereto, two armatures disposed adjacently between said pole pieces, 75 circuit controlling means for one of said armatures, main end plates attached to said field frame for directly and indirectly carrying bearings for said armatures, a supplemental end plate attached to one of said 80 main plates and carrying a bearing for one of said armatures and with said main plate forming a housing for said circuit controlling means and means for driving one armature from the other, as described. 85

4. In combination, a field frame with pole pieces attached thereto, two armatures disposed adjacently between said pole pieces, end plates attached to said field frame for supporting said armatures, a supplemental 90 plate attached to one of said end plates, an auxiliary plate attached to said supplemental plate and carrying members included in the working circuit of one of said armatures, 95 studs secured to but insulated from one of said plates, passing through and beyond said supplemental plate and adapted to be secured to the members within the auxiliary plate included in the working circuit of one of said armatures and a cover for said auxiliary plate. 100

5. In combination, a field frame with pole pieces attached thereto, two armatures disposed adjacently between said pole pieces, end plates attached to said field frame, a 105 supplemental plate attached to one of said end plates and adapted to carry a bearing for one of said armatures, a housing attached to the other of said end plates and carrying one of the bearings for the other of 110 said armatures, bearings in both of said main end plates for said armatures, an auxiliary plate mounted on said supplemental plate and carrying members included in the working circuit of one of said armatures, 115 studs insulated from but securely fastened to both of said main end plates, said studs in one end plate adapted to connect with the current carrying members in said auxiliary plate, said studs in the other end plate being adapted to be connected in the working circuit of said armature and a cover plate for both the auxiliary plate and the housing. 120

6. In combination, a field frame with pole pieces attached thereto, a high tension and 125 low tension armature disposed adjacently between said pole pieces, end bearing plates adapted to be fastened to said field frame, one of said end plates carrying a bearing for the low tension armature and a supple- 130

mental plate which carries a bearing for the high tension armature, the other of said end plates carrying a bearing for the high tension armature and a housing for the commu-

5 tator of said low tension armature, said housing carrying a second bearing for the low tension armature, an auxiliary plate carried by the said supplemental plate, circuit controlling members mounted within said

10 auxiliary plate and rigid electrical connecting means adapted to be connected to said members and extending to the interior of said end plate, circuit connecting studs mounted on the other of said end plates and
15 caps for covering both sets of connecting studs for the purpose described.

7. In combination, a field frame with pole pieces attached thereto, a high tension armature and a low tension armature disposed adjacently between said pole pieces, main end plates attached to said field frame, a supplemental plate attached to one of said main end plates, a gear on said low tension armature, adapted to mesh with a gear on said high tension armature, said gears being housed within said main and supplemental plates, governing mechanism mounted on said low tension armature shaft, and housed within said supplemental plate, an auxiliary plate mounted on said supplemental plate and carrying members included in the working circuit of said low tension armature and controlled by said governing mechanism, a circuit breaker mounted on the shaft of said high tension armature and a timing device for said circuit breaker on said supplemental plate and covers for the mechanism within the auxiliary plate and the circuit breaker.

40 8. In combination, a field frame with pole
pieces attached thereto, a high tension arma-
ture and a low tension armature disposed
adjacently between said pole pieces, main
end plates attached to said field frame, one
45 of said end plates carrying a housing for
the commutator of said low tension arma-
ture, and brush holders for said high ten-
sion armature, said commutator housing
carrying brushes for said low tension arma-
ture, the other of said main end bearing
50 plates carrying a supplemental plate, an
auxiliary plate carried on said supplemen-
tal plate, gears on both said armatures for
driving one from the other, said gears being
55 housed by one of the main end plates and
said supplemental plate, governing mech-
anism mounted on said low tension armature
shaft and housed within said supplemental
plate, circuit controlling members mounted
60 within said auxiliary plate and controlled
by said governing mechanism and rigid con-

necting means mounted on both main end plates for connecting the circuit controlling members with the low tension armature and external circuits.

65

9. In combination, a field frame having two sets of pole pieces attached thereto, a high tension armature and a low tension armature disposed adjacently between said sets of pole pieces, main end plates attached 70

to said field frame, a supplemental plate attached to one of said main end plates, a bearing in said last mentioned main end plate, a gear having a hub adapted to fit rigidly into said bearing, a gear on said

high tension armature adapted to drive the first mentioned gear, both of said gears being housed by the main end plate and said supplemental plate, governing mechanism operated by the gear on said low tension

armature, an auxiliary plate mounted on said supplemental plate and carrying switch members operated by said governing means and means drivingly connecting the hub of said gear to said low tension armature shaft 85

whereby said armature may be removed from the field frame without disturbing said gears, governing mechanism and auxiliary plate.

10. In combination, a field frame with 90
pole pieces attached thereto, two armatures
for the generation of different kinds of cur-
rent disposed adjacently between said pole
pieces, main end plates attached to said 95
field frame and pole pieces for directly and
indirectly supporting said armatures, a sup-
plemental plate of substantially the same
area as and attached to one of said main 100
armature supporting plates and an auxiliary
plate attached to said supplemental plate,
and a cover for the auxiliary plate, substan-
tially as and for the purpose described.

11. In combination, a field frame with
pole pieces attached thereto, two armatures
disposed adjacently between said pole pieces, 105
main end plates attached to said field frame,
a supplemental plate extending substantially
over the whole surface of one of said
main plates and rigidly fastened thereto, a
housing fastened to the other of said main 110
plates, bearings for said armatures carried
in the main and supplemental plates and
housing, an auxiliary plate rigidly attached
to the upper part of said supplemental plate
and a removable cover therefor, a timing 115
device mounted on the lower part of said
supplemental plate and a cover for the timing
mechanism, as and for the purpose de-
scribed.

In witness whereof, I affix my signature. 120

JAMES M. WILSON.
